UNITED STATES PATENT OFFICE

WILLIAM H. HICKEY, OF WASHINGTON, DISTRICT OF COLUMBIA

DESIGN FOR A HAT BADGE

Application filed October 8, 1931. Serial No. 41,343. Term of patent 3½ years.

To all whom it may concern:

Be it known that I, WILLIAM H. HICKEY, a citizen of the United States, residing at 1237 Eighteenth Street, N. E., in the city of Washington, D. C., have invented a new, original, and ornamental Design for Hat Badge, of which the following is a specification, reference being had to the accompanying drawing, forming part thereof.

A triangle in form with a scroll on lower edge of each side. The inner lined triangle is done in red with gold lettering on three sides. The center is white and the Bar across

the white is finished in blue, with the word "Guide" in gold letters. The entire design is gold plated all over with hard enamel on the whole front in colors. Red, white, and blue as described above.

The figure is a plan view of a hat badge, showing my new design. The hat badge is constructed of thin, flat material.

I claim:

The ornamental design for a hat badge, as shown and described.

WILLIAM H. HICKEY.
